UNITED STATES PATENT OFFICE.

DAVIS MARINSKY, OF NEW YORK, N. Y.

FASTENER TAPE.

Application filed March 29, 1923. Serial No. 628,544.

To all whom it may concern:

Be it known that I, DAVIS MARINSKY, a citizen of the United States, and a resident of the borough of the Bronx, Bronx County, 5 city and State of New York, have invented an Improvement in Fastener Tape, of which the following is a specification.

My present invention relates to fastener tape, particularly garment-fastener tapes, 10 such as hook and eye tapes, and aims to provide devices of the general character designated above which shall be stronger than the devices hitherto devised for the same general purposes; which shall be less liable 15 to catch, scratch or tear the garment or other articles to which they may be attached, or the hands of the persons washing or otherwise handling such articles; which shall be less liable to permit or cause the rusting of such 20 fasteners or of their attaching means, where the fasteners or the attaching means are made of metal; which shall be more convenient and neater in appearance than the 25 similar devices hitherto proposed for use for the same purposes; and which shall effect substantial economies in the fabrication of the garments or other articles to which they may be applied, while producing a finished garment or other article of superior neat- 30 ness and attractiveness.

In the accompanying specification I shall describe an illustrative embodiment of my method for making fastener tape in accordance with the principles of the present invention, the resulting illustrative embodiment of fastener tape being described in the accompanying specification and shown in the annexed drawing. In the specification I shall also describe an illustrative embodiment of my method for fabricating garments or equivalent articles incorporating the aforesaid illustrative embodiment of fastener tape, all in accordance with the principles of the present invention, the resulting illustrative embodiment of garment or equivalent article being described in the accompanying specification and shown in the annexed drawing. It is, however, to be clearly understood that my invention is not limited to the specific embodiments thereof herein shown and described for purposes of illustration only.

Referring to the drawing, wherein I have shown the aforesaid illustrative embodiments of the fastener tape and garment or equivalent article incorporating the same,

in the practice of the aforesaid illustrative embodiments of my method of making fastener tapes and incorporating the same in garments or equivalent articles.

60

Fig. 1 is a plan view of the aforesaid illustrative embodiment showing the eye-tape portion of a hook and eye tape during one stage of its fabrication;

65

Fig. 2 is a view similar to Fig. 1 of the eye-tape shown therein during a subsequent stage of its fabrication;

70

Fig. 3 is a view similar to Figs. 1 and 2 of the eye-tape completed;

75

Fig. 4 is a plan view of the aforesaid illustrative embodiment showing the hook-tape portion of the hook and eye tape;

80

Fig. 5 is a plan view of a portion of a garment having an unfinished edge;

85

Fig. 6 is a view similar to Figs. 1, 2 and 3 showing the eye-tape illustrated therein applied to the unfinished edge of a garment shown in Fig. 5 of the drawing;

90

Figs. 7 and 8 are detail cross sectional views on enlarged scales, taken along lines 7—7 and line 8—8 of Fig. 6, respectively;

95

Fig. 9 is a cross sectional view of the two tape portions shown in position on a garment; and

100

Fig. 10 is a perspective view, and Fig. 11 a cross-sectional view of a modification.

105

Before describing the aforesaid illustrative embodiments of the present invention in detail, it may be desirable briefly to point out certain disadvantages and shortcomings of the prior art to which the present invention relates. Taking hook and eye tape as an illustrative example, the eye-tape portion of such tape, as hitherto constructed, consists of a series of eyes attached to one side of the tape by rivets or eyelets passing through the tape and through the perforated portions of the eyes. The other side of the tape, which is the side which is in contact with the material of the garment or other article to which the tape is to be applied, will therefore be in contact with the metal fastening means employed for attaching the eyes to the tape, with the result that the metallic fastening means will have a tendency to catch, scratch, tear and rust the garment portions with which they come into contact. The hook-tape portions of the hook and eye tapes, as hitherto constructed, comprise a series of hooks attached to one side of the tape so that the hooked ends of the hooks are loose and readily raised away

110

from the stationary tape into such positions as make it highly inconvenient, or, even, under some conditions, almost impossible to hook and unhook the fasteners and the associated garment portions.

I overcome the foregoing disadvantages by means of the present invention, at the same time accomplishing certain highly desirable and advantageous results hereinafter set forth. In the practice of the aforesaid illustrative embodiment of my invention for making fastener tape, I provide, first, a supporting tape 10 and an auxiliary or covering tape 11. The tape 10 is of any desired width and is generally made of comparatively heavy and strong material. The tape 11, on the other hand, while being preferably of substantially the same width as the tape 10, is preferably of a lighter material, so as to be readily foldable, for purposes subsequently set forth in detail herein.

I next provide a series of fasteners, such as eyes, 12, in the specific example herein described, and also a plurality of attaching means, preferably consisting of metallic attaching members, such as double rivets or eyelets 13, having the tapering sleeve-like portions 14 and 15 provided with the apertures 14' and 15', respectively.

By any suitable means, whether by hand or by machine, not here deemed necessary to be shown or described, the eyes 12 are placed on one side of the supporting tape 10, such as the outer side of the supporting tape, and the attaching members 13 placed on the outer side of the auxiliary tape 11, in positions of the apertures 14' and 15' corresponding to the apertures 12' and 12'' of the eyes 12. Any suitable riveting means, whether hand or machine operated, not here deemed necessary to be shown or described, may now be employed to fasten the eyes in place on the supporting tape 10 by means of the attaching members 13. The attaching members have the portions 14 and 15 thereof passing through the auxiliary tape 11, the supporting tape 10, and into and through the apertures 12' and 12'' of the eyes 12, as more clearly shown in Fig. 6 of the drawing. The upper faces of the portions 14 and 15 are headed or beaded over the portions 12' and 12'' of the eyes 12, thus holding the eyes firmly in place.

It will be noted that in the example given, the supporting and auxiliary tapes overlap for portions only of their respective widths, leaving the free portion 10' of the supporting tape and the free portion 11' of the auxiliary tape. I now fold under the free portion 11' of the auxiliary tape 11 to provide a portion 16 which comprises a finished outer edge for the auxiliary tape, as more clearly shown in Fig. 2 of the drawing. The free portion of the auxiliary tape 11, now having the finished outer edge 16, is again folded under,

as more clearly shown in Fig. 3 of the drawing, to provide a covering portion 17 which serves to cover and protect the lower face portions of the metallic fastening members 13. It will thus be noted that the folded over portion of the auxiliary tape 11 forms a garment-fabric-receiving pocket open in a direction from the attaching means 13 opposite to the direction in which the eyelets or other fasteners 12 extend.

For the hook-tape portion of the hook and eye tape, I provide a supporting tape 20, a retaining tape 21, and hooks 22 carried by the supporting tape. The hooks 22 are provided with rings, apertures or other means, 22' and 22'', for attaching the same to the supporting tape 20. For this purpose I provide any suitable, such as metallic, attaching means which may be in the form of double rivets or eyelets 23, like the rivets or eyelets 13 used for attaching the eyes to their supporting tape. The fastening means 23 include tubular riveting portions 24 and 25 provided with the apertures 24' and 25', respectively.

The retaining tape 21 is provided with slots or apertures 21' for engagement with the hooked portions of the hooks 22. In attaching the hooks to the supporting tape 20, the tubular portions 24 and 25 of the fastening means 23 are forced through the supporting tape so as to pass through the ringlets or apertures 22' or 22'' of the hooks 22. The upper portions of the parts 24 and 25 of the attaching means are then beaded or headed over, about the apertures 24' and 25', to hold the hooks in place on the supporting tape 20. During this operation the hook portion of the hook 22 may be threaded through the slot or other aperture 21'.

From the foregoing description it will be apparent that I have devised a method whereby I may, in a very simple and economical manner, provide fastener tape, such as hook and eye tape which will afford the necessary protection or covering for the metallic fastening members used to attach the eyes or other fastening devices to the supporting tape. It will also be apparent that the resulting eye-tape itself will be such as to prevent the metallic attaching members from catching, scratching, tearing or rusting the garment portions to which the tape may be attached. The hooks of the hook-tape portion of the hook and eye tape are prevented from being raised away from the supporting tape into such positions that the hooks and eyes can only with difficulty be fastened and unfastened. The resulting hook and eye tape itself is exceedingly neat and attractive in appearance, is stronger than the tapes hitherto employed for the same purpose, and greatly facilitates the fabrication of the garments to which the tape may be applied, as will now be described in greater detail.

In Fig. 5 of the drawing I have shown a portion 30 of a garment generally indicated by reference character G and having the unfinished edge 31. In attaching the tape shown in Figs. 1, 2 and 3 of the drawing, and generally indicated by reference character T, to the garment G, I insert the unfinished edge 31 of the garment between the portion 10' of the supporting tape 10 and the overlapping portion 17 of the auxiliary tape 11. I now pass a line of stitching, indicated by reference character 32, through the portion 10' of the tape 10 and the overlapping portion 17 of the tape 11, preferably by passing this line of stitching through the finished edge portion 16 of the portion 17 of the tape 11, through the edge portion 31 of the garment, and through the corresponding portion 10' of the supporting tape. It will be noted that the edge of the auxiliary tape 11 corresponding to the adjacent edge of the supporting tape along those portions of the auxiliary and supporting tapes which are in contact is offset from the edge of the supporting tape just referred to, thus permitting the neat and ready application of the fabric 30 of the garment G, without unduly increasing the thickness of the union between the fastener tape and the material of the garment.

In attaching the hook-tape portions of the hook and eye tape to the garment, a single stitch 40 may be passed through the supporting and retaining tapes 20 and 21, respectively, and through the garment, as shown more clearly in Fig. 9 of the drawing.

By means of the foregoing method I am enabled, in an exceedingly economical and expeditious manner, to incorporate the fastener, such as the hook and eye, tape of the present invention in a garment or similar article. This I may do with a garment having an unfinished edge portion, without finishing said edge portions, but still obtaining, by means of the present invention, a garment having the neatness and attractive appearance of a carefully finished garment. There is thus effected a considerable saving in labor and material. The finished garment, having incorporated therein the fastener tape of the present invention, possesses many important advantages, in that the fastener tape is very strongly attached to the garment and the metallic fastening members, in the case of the eye-tape, are within what is really a tubular fabric portion, thus preventing the metallic fastening members from catching, scratching, tearing or rusting the portions of the garment adjacent thereto, and also the hands of the persons washing or otherwise handling such garments. It will be noted that the hooks of the hook-tape portion of the hook and eye tape are prevented by the re-

taining tape from being raised away from the supporting tape into such positions that the hooks and eyes, and the associated garment portions, can only with difficulty or serious inconvenience be attached and detached. As a result, also, of the economies in manufacture effected by the present invention, I am enabled to turn out a superior garment at a much lower cost than has hitherto been possible.

Instead of using two separate tapes, such as the supporting and retaining tapes, for making the hook-tape portion of the hook and eye tape, I may use a single tape, of which one portion may be called the supporting tape or supporting tape portion, and the other portion the retaining tape or retaining tape portion. Such a construction has been shown in Figs. 10 and 11 of the drawing, in which the main portions of the hooks are supported by the supporting tape or supporting tape portion 20^a of the tape, generally designated by reference character 20^b, while the hook portions of the hooks pass through slots 20^c in the retaining tape or retaining tape portion 20^e. This construction avoids the use of an additional tape, while still preserving all of the essential features of construction and the advantages of the hook-tape described above.

What I claim as my invention is:

1. Fastener tape comprising a supporting tape, a series of fasteners carried by said supporting tape on one side thereof, means for attaching said fasteners to said supporting tape, and an auxiliary tape attached by said attaching means along a portion of the width thereof to the remaining side of said supporting tape and having a portion at least of the remaining width thereof folded over so as to cover said attaching means.

2. Fastener tape comprising a supporting tape, a series of fasteners carried by said supporting tape on one side thereof, means for attaching said fasteners to said supporting tape, and a separate auxiliary tape attached along a portion of the width thereof to the remaining side of said supporting tape and having a portion at least of the remaining width thereof folded over so as to cover said attaching means, the free outer portion of the remaining width of said auxiliary tape being folded under so as to provide the same with a finished free outer edge.

3. The method of fabricating fastener, such as hook and eye, tape which comprises positioning a plurality of fasteners on one side of a supporting tape by attaching means serving also to attach an auxiliary tape on the other side of said supporting tape, and thereafter folding over said auxiliary tape so as to overlie said attaching means.

4. Hook-tape comprising a supporting

tape, a hook-retaining tape, and a plurality of hooks attached to said supporting tape and each having the hooked portion thereof positively engaging said hook-retaining tape.

5. Fastener tape comprising a supporting tape portion, a fastener-retaining tape portion provided with a plurality of slots therein, and a plurality of fasteners attached 10 to said supporting tape portion and each having a part thereof engaged by one of the slots of said fastener-retaining tape portion.

6. Fastener tape comprising a supporting tape, a series of fasteners carried by said 15 supporting tape on one side thereof, means for attaching said fasteners to said supporting tape, and an auxiliary tape attached by said attaching means along a portion of the width thereof to the remaining side of said 20 supporting tape and having a portion at least of the remaining width thereof folded over so as to cover said attaching means

to thus form a garment-fabric-receiving pocket open in a direction from said attaching means opposite to the direction in 25 which said fasteners extend.

7. Fastener tape comprising a supporting tape, a series of fasteners carried by said supporting tape on one side thereof, means 30 for attaching said fasteners to said supporting tape, and an auxiliary tape attached by said attaching means along a portion of the width thereof to the remaining side of said supporting tape and having one edge thereof offset from the corresponding edge 35 of the supporting tape and having a portion at least of the remaining width thereof folded over so as to cover said attaching means.

In testimony whereof I have signed my 40 name to this specification this 19th day of March, 1923.

DAVIS MARINSKY.
